UNITED STATES PATENT OFFICE.

WILLIAM B. OLIVER, OF SHARON HILL, PENNSYLVANIA, ASSIGNOR TO OLIVER MANUFACTURING COMPANY, OF PHILADELPHIA, PENNSYLVANIA, A CORPORATION OF PENNSYLVANIA.

SUPPORT.

No. 858,820.

Specification of Letters Patent.

Patented July 2, 1907.

Application filed June 15, 1906. Serial No. 321,889.

To all whom it may concern:

Be it known that I, WILLIAM B. OLIVER, of Sharon Hill, in the county of Delaware and State of Pennsylvania, have invented certain new and useful Improvements in Supports, whereof the following is a specification, reference being had to the accompanying drawings.

My invention relates to a support, pivotally mounted and so balanced by means of self-contained spring devices, as to be capable of remaining in a state of equilibrium when placed in any of the positions which are within the range of its pivotal adjustment. The most extended use of supports of this general character at the present time, is as an adjunct to, or carrier for, the ordinary desk telephone instrument.

15 This organization, as a whole, involves the use of somewhat cumbersome parts, and one object of the present invention is to simplify the structure by the elimination of certain relatively unimportant features, thus directly combining the transmitter casing and the receiver with the self-balancing support, while at the same time permitting the use of the transmitting and receiving elements, in the form commercially employed in the desk instruments referred to.

20 Another object of my invention is to advantageously modify the self-contained balancing elements, dispensing with some of the features heretofore employed for obtaining the differential action thereof.

Another object of my invention is to so organize a base and a self-balancing standard whose foot is carried by said base, as to permit the base to be attached either to a horizontal or to a vertical surface, and the standard to be mounted thereon in any one of a great number of positions.

35 Many of these features may obviously be made available broadly in this general class of supports, and hence are not to be considered as restricted to the particular form now indicated, as preferable for the entire organization.

40 In the accompanying drawings, Figure I, is a view, partly in side elevation and partly in a vertical axial section, of the support, and the telephone elements combined therewith, showing the foot of the support, but not the base on which said foot is preferably mounted. Fig. II, is a view in vertical axial section through the upper portion of the support, the plane of section being at right angles to that shown in Fig. I. Fig. III, is a transverse section through the support on the line III, III, in Fig. I. Fig. IV, is a perspective view in detail of the adjusting devices for the self-contained spring. Fig. V, is a front view of the upper end of the support, showing the transmitter casing, the main receiver hook, and the auxiliary receiver hook. Fig. VI, is a similar front view of the lower end of the support and its foot. Fig. VII, is a view of the base and the

foot of the support, shown in side elevation, the base being indicated as applied to a vertical wall. Fig. VIII, is a view in side elevation, indicating the base as applied to a horizontal surface, and showing the foot and a portion of the lower end of the support, together with the adjunctive coupling piece which is employed under these conditions of mounting. Fig. IX, is an end elevation of the coupling piece, the direction of view being toward the right in Fig. VIII. Fig. X, is an end elevation of the base, showing it as applied to a vertical wall, but in a direction at right angles to that shown in Fig. VII. Fig. XI, is a view, in side elevation, of the foot and standard of a modified form of the device, adapted to be used with a special type of transmitter casing, which permits a relatively smaller amount of overhang at the top of the support than is characteristic of the type shown in Fig. I. Fig. XII, is a view, in side elevation, of the foot of said modified form together with the base, which in this instance, is shown as applied to a vertical wall.

The standard, or support proper, is of substantially the same general organization in all the figures, and terminates at its lower end in a foot, which is adapted to be pivotally mounted, meditately, or immediately, upon a separable piece, which I term the base. Hence, I will preface the description of the standard itself by description of the base and the adjunctive coupling piece which permits adjustment in any one of several positions.

The base (see Figs. VII, VIII, and X), comprises a plate 1, having preferably a hollow raised back, forming a chamber 2, in which the induction coils may conveniently be inclosed. A raised arm 3, projects beyond the attaching face and terminates in a cylindrical head 4. A central pin 5, projects from the face of said head, and is provided at its outer extremity with a threaded cavity 6, whose purpose will be stated hereafter. A circumferential groove 8, (shown in dotted lines in Figs. VII, and VIII), is formed around said pin about midway of its length, and a pair of diametrical lugs 9, 9, are formed on the face of the head 4, extending outward from the pin 5, to the periphery of the face. Said lugs are preferably beveled as indicated. A washer 10, having recesses 11, corresponding in depth to the height of the lugs 9, fits snugly upon the face of the head 4, and is provided on its upper side with a stop or projection 12. The lower end portion 13, of the standard (which I term the foot), is formed with a socket adapted to receive the pin 5, and a lateral set screw 14, is mounted in the foot in proper relation to engage in the groove 8, of the pin 5, so that when the foot of the standard is mounted in position, with the washer 10, intervening between it and the head 4, the parts are secured together, but are rotatable upon the pin 5, throughout a comparatively large

range, play of the washer 10, with relation to the lugs 9, of the head 4, being permitted by reason of the recesses 11.

The foot of the standard is normally to be considered 5 as a vertical member, and hence when the base is secured against a vertical surface, and with its pin 5, perpendicular (as shown in Fig. VII), the foot is mounted directly upon the pin 5. When, however, the base is secured to a horizontal surface (as shown in Fig. VIII), or 10 with its pin 5, standing in a horizontal position, (as shown in Fig. X), it is necessary, in order to preserve the vertical position of the foot 13, to interpose a coupling piece. This coupling piece is shown in Figs. VIII, and IX, and comprises two members 15, and 16, arranged 15 ranged at a right angle to one another, and corresponding in diameter to the head 4, of the base. The region of union between the members 15, and 16, is preferably of rounded configuration, as indicated at 20, in Fig. VIII. The member 15, has a socket 7, adapted to receive the pin 5, of the base, the opening of said socket extending through the union 20.

Upon the end face of the member 15, and adjacent to the opening of the socket 7, are four radial slots 21, arranged in quadrant positions, and corresponding in cross-section with the radial lugs 9, upon the base. The member 16, has a central pin 17, with a circumferential groove 18, and diametrical lugs 19, 19. The coupling piece can be mounted upon the pin 5, of the base, in any of the quadrant positions which permit the registry 30 of the slots 21, with the lugs 9, and can then be secured rigidly by means of the screw 22, which engages in the threaded cavity 6, of the pin 5. It will thus be seen that when the coupling piece is mounted for instance, in the position shown in Fig. VIII, the member 16, with 35 its pin 17, stands vertically and reproduces the same general conditions for mounting the standard, as existed when the base was arranged upon a vertical surface, as shown in Fig. VII. Hence the foot 13, of the standard will fit vertically upon said pin 17, and can be relatively secured thereto by means of the set screw 14, which now engages in the groove 18.

I will now describe the preferred organization of the standard and balancing mechanism. The standard comprises a foot, two telescoping tubular parts, (which I term the upper and lower stems), and an overhanging top portion. The foot 13, carries a segmental cam piece 24, stoutly supported by means of a web 25. The upper end of the foot is cut away on each side (see Fig. VI), so as to form flat bearing faces 26, 26, adapted to receive 45 the bifurcated and rearwardly curved ends 27, 27, of the lower stem 28, which are rotatably secured to the foot by means of a pivot 29. Said pivot is provided with a thumb nut and spring lock washer 30, in order to permit a regulated frictional engagement with the bearing faces and thus to assist if necessary the devices 50 for maintaining equilibrium. A stop 23, limits the rearward movement of the standard. Said balancing devices are organized as follows:—The lower stem 28, which is preferably tubular, as shown, carries a coiled 55 spring 31, whose upper end abuts against the ring nut 32, (see Fig. IV), which is mounted upon the threaded tubular piece 34. The upper end of the piece 34, is slotted and the portions 35, corresponding with the extent of the slots are turned outwards into a horizontal 60 position. These portions 35, engage beneath the over-

hanging flange 37, formed on the upper end of the lower stem 28, so that the tubular piece 34, is rotatably supported against upward thrust. The ring nut 32, carries a pin 38, which engages in a vertical slot 40, formed in the lower stem 28, and preferably extending throughout substantially the greater portion of its length. 70

The lower end of the spring 31, exerts pressure against the bearing block or shoe 42, which slides freely within the lower stem 28. Holes 43, are formed through said shoe 42, to permit the passage of the telephone 75 wires, which extend down through the standard and emerge at the lower end thereof, as will be described hereafter. The lower surface of the shoe 42, is adapted to ride upon the curved surface of the cam piece 24, when the standard is turned from a vertical position, as 80 indicated in dotted lines in Fig. VIII.

The lower stem 28, has a relatively wide slot 45, to permit it to be turned down over the cam 24, and the configuration of the cam surface is such that as the standard is turned more and more toward a horizontal 85 position, the shoe 42, is forced upwards within the standard, thus compressing the spring 31, with a progressively increasing ratio. By a proper correlation between the strength of the spring, the curve of the cam, and the weights of the supported members, substantial equilibrium may be maintained in any position of the standard, as will readily be understood. The upper stem 46, also preferably tubular, is fitted telescopic- 90 ally upon the lower stem, being slotted, as indicated at 47, and provided with a screw clamping band 48, so that the two parts may be maintained in any given longitudinal adjustment with relation to each other. The upper stem 46, itself is preferably constructed in two parts, secured together at the region 50. The upper portion of the upper stem is hollow and is adapted to 100 contain in its interior the circuit wires and contact pieces characteristic of any ordinary desk telephone instrument. The construction and general organization of these being well understood, it is not deemed necessary to describe the same, except that so far as 105 they represent peculiarities due to their present embodiment. Near the upper end of the upper stem 46, an inclined slot 51, is formed to permit the up and down movement of the shank 52, of the receiver hook 53, said shank being pivotally mounted at 54, on an inclined 110 plate 55, which affords a bearing surface parallel to the inclination of the slot 51. The receiver hook 53, is mounted upon the shank 52, by means of a swivel connection 56.

The purpose of giving an inclination to the slot 51, and pivoting the shank upon an axis inclined with relation to the axis of the standard and also of employing a swivel mounting for the hook 53, is to insure the proper action of gravity upon the parts, irrespective of the inclination of the standard, as a whole, to the perpendicular. As before stated, the contact pieces, et cetera, may be of any of the well known types, the spring 58, having its upper end 57, of such configuration as to bear laterally and upwardly against the shank 52, of the receiver hook. 115 120

The position of the parts shown in the various figures is that which occurs when the receiver 60, is lifted from the hook 53, and the spring 58, has thrown the shank 52, of the hook, to its uppermost position in the slot 51. Under these circumstances, the spring mem- 130

ber 58, presses the stud 61, against the switch 62, and thus establishes the circuit between said switch member and the line conductor 65. When, however, the receiver 69, is placed upon the hook 53, the action of gravity causes the latter to descend the incline of the slot 51, and the shank 52, of the hook forces the spring 58, in the corresponding direction, so that the pressure of the stud 61, upon the switch member 62, is relieved and the latter springs out of contact with the member 65.

10 It will be noted, that by reason of the swiveled connection 56, between the hook 53, and its shank 52, the receiver will hang in a vertical position, no matter what may be the inclination of the standard to the vertical, and furthermore, by reason of the inclined axis 15 upon which the shank 52, is pivoted, and the freedom allowed by the inclined slot, the proper gravitational effect of the receiver is always insured.

The upper end 68, of the standard is reduced in size and bent outwardly so as to form an overhanging support for the telephone transmitter casing 70. In the instance shown, this casing is of the ordinary type found in desk instruments and has a rearwardly projecting part 71, which is pivotally connected at 72, to a curved arm 73. Said arm 73, terminates in a cylindrical boss 25 74, which is pivoted upon a vertical axis by means of a screw pin 75, secured to a downwardly depending piece 76, which is pendulously secured to the overhanging support 68, by means of the horizontal pivot 69. It will thus be seen that the connection between the transmitter casing 70, and the support 68, is of such a character as to permit the pendulum-wise swing of the casing, which maintains it in its proper relation in all the various positions of the support with reference to the vertical, and also that the transmitter casing and mouth piece are revoluble upon a vertical axis, thus greatly adding to the convenience of the device. An auxiliary receiver hook 79, projects laterally from the part 74, so as to both rotate and swing therewith, the purpose of such auxiliary hook being to permit the hanging up of the receiver when it has been removed from its spring actuated hook 53, and during the interval when it may be desired to maintain the talking circuit, although the telephone itself is temporarily not in actual use.

In Fig. I, in the solid lines, the receiver is shown as 45 supported upon said auxiliary hook 79, but in the dotted lines the auxiliary hook is indicated without the receiver.

In the alternative type of the device shown in Figs. XI, and XII, the only substantial modifications are 50 those which are due to the different organization of the transmitter casing. Instead of utilizing the transmitter casing of the ordinary desk instrument, the casing 80, in this instance, is of a special type, which has no rearwardly projecting point of support, but is provided 55 on its upper side with a vertical projection 81, rotatively secured within a coupling 82, which is pendulously supported by the horizontal pivot 83, connected to the overhanging top 84, of the self-balancing support indicated comprehensively at 85. The auxiliary receiver hook 86, is in this instance, attached to the lower side of the casing 80, by means of the downwardly depending stud 87. By this arrangement, as in the other case, the transmitter casing with its mouth piece and the auxiliary receiver hook, are rotatively 60 mounted upon a vertical axis, and also swing pendu-

lum-wise upon the pivot 83. The general organization of the self-balancing support may be the same as that just described but it will be noted that the overhanging top portion thereof is of less lateral extent than in the type shown in Fig. I, this modification being permitted by reason of the absence of projecting members at the rear of the transmitter casing. The difference in the center of gravity due to the diminished amount of overhang must of course be met by a corresponding modification of the cam surface 86, 75 mounted upon the foot 88. Furthermore, the lower extremity of the standard, instead of being provided with the rearwardly projecting curved parts shown in Fig. I, may be straight as indicated at 89, so that the axis of the standard when in a vertical position, is coincident with the axis of the foot, instead of being out of line therewith, as in the type shown in Fig. I.

In both forms of organization it will be noted that the auxiliary receiver hook is at the right hand of the mouth piece as faced by the user, and that it maintains 85 its definite position with relation to the mouth piece regardless of the swinging or rotating movement of the transmitter casing, thus avoiding confusion with the normal or regular receiver hook which is usually located at the level of the mouth piece. In both types of supports, the circuit wires lead down through the standard and pass through the openings 43, in the shoe 42, emerging at the foot and being thence led into the base-piece, through the opening 90, for connections with the induction coils, not shown.

To avoid prolixity in my claims I use the term "self-balancing support", as meaning a pivotally mounted structure of the kind described, controlled by self-contained spring devices, which together with the friction of the moving parts maintain the structure and 100 the elements carried thereby practically in a state of equilibrium as against the action of gravity in any of the various positions which the standard may assume.

I claim:—

1. In an adjustable support, comprising a foot provided 105 with a socket, the combination with said foot; of a base piece having a pin or stud projecting therefrom; a substantially right-angled coupling piece having in one extremity a socket adapted to receive a pin or stud projecting from said base piece and at the other extremity a pin or stud adapted to enter the socket of the foot; and means for maintaining said coupling in a plurality of predetermined rotative positions with reference to the base piece.

2. In a self-balancing support comprising a foot provided with a socket, the combination with said foot; of a base piece having a pin adapted to enter the socket of the foot; a projecting lug adjacent to the pin; a washer having a recessed portion adapted to receive said lug; and means for securing the foot against displacement 110 while permitting the rotation of the foot upon the pin.

3. In a self-balancing support comprising a foot provided with a socket, the combination with said foot; of a base having a projecting pin; a lug adjacent to said pin; a coupling piece comprising two projections arranged substantially at a right angle to one another, one of said projections being provided with a socket adapted to receive said pin, and with a recess adapted to receive said lug; a pin extending from the other of said projections and adapted to enter the socket of the foot; and means for securing the parts against displacement while permitting the rotation of the foot upon the pin.

4. In a self-balancing support comprising a foot provided with a socket; the combination with said foot; of a base having a projecting pin; a pair of diametrical lugs 135

- adjacent to said pin; a coupling piece comprising two projections arranged substantially at a right angle to one another, one of said projections being provided with a socket adapted to receive said pin, and with recesses arranged at quadrants and adapted to receive said lugs; a pin extending from the other of said projections and adapted to enter the socket of the foot; and means for securing the parts against displacement while permitting the rotation of the foot upon the pin.
10. 5. The combination with a foot; of a cam projecting laterally therefrom; a standard pivoted to turn in the plane of said cam; a spring carried by said standard and having one end in engagement therewith, and means whereby the other end of the spring is maintained in operative relation to the cam surface.
15. 6. The combination with a foot; of a cam projecting laterally therefrom; a standard pivoted to turn in the plane of said cam and provided with an interior abutment; a spring carried by said standard and having one end in engagement with said abutment; and a shoe engaging the other end of said spring and arranged in operative relation to the cam surface.
7. In a self-balancing support of tubular form, the combination of a cam; a coiled spring inclosed within
- said tubular support; an adjusting screw and collar at 25 the upper end of said spring; and a longitudinal movable plunger or shoe, arranged at the lower end of said spring, and adapted to operatively engage said cam; said shoe and screw being perforated to permit the passage of circuit wires to electrically operative members at the upper 30 end of the support.
8. In a telephone support, the combination of a foot; a cam projecting laterally therefrom; a spring-balancing standard bifurcated at its lower end for attachment to the foot and co-operating with said cam; a bolt passing 35 through the foot and the bifurcated end of the standard; and a spring washer and nut carried by said bolt, whereby the spring balancing action may be supplemented by an evenly regulated friction in compensation for variable loads at the outer end of the balancing standard.

In testimony whereof, I have hereunto signed my name, at Philadelphia, in the State of Pennsylvania, this 13th day of June, 1906.

WILLIAM B. OLIVER.
